UNITED STATES PATENT OFFICE.

SOREN CHRISTIAN REPSHOLDT, OF OMAHA, NEBRASKA.

TRAFFIC-SIGNAL TOWER.

1,359,529.

Specification of Letters Patent. Patented Nov. 23, 1920.

Application filed July 15, 1919. Serial No. 311,112.

To all whom it may concern:

Be it known that I, SOREN CHRISTIAN REPSHOLDT, a citizen of the United States of America, residing at Omaha, in the county of Douglas and State of Nebraska, have invented certain new and useful Improvements in Traffic-Signal Towers, of which the following is a specification.

This invention relates to new and useful 10 improvements in traffic signal towers especially adapted for street crossings provided with traffic signals readily operable by a crossing officer positioned within or outside the tower.

15 The primary object of the invention is the provision of a signal tower having novel means for the display of orders at diametrically opposite sides of the tower and viewable in the directions of the oncoming 20 traffic.

A further object of the invention is the provision of an elevated tower at street intersections having improved means for actuating selectively a pair of oppositely disposed crossing signals.

With the above general objects in view and others that will become apparent as the nature of the invention is better understood, the same consists in the novel form, combination and arrangement of parts herein-after more fully described, shown in the accompanying drawings and claimed.

In the drawings, forming a part of this application and in which like reference 35 characters refer to corresponding parts throughout the several views,

Figure 1 is a perspective view of the invention illustrated in use at a street crossing and of a form to be actuated from a distant 40 station,

Fig. 2 is an enlarged elevational view of a signal tower constructed in accordance with the present invention and designed to accommodate an operator therein,

45 Fig. 3 is a fragmentary perspective detail view of the device shown in Fig. 2 and clearly showing the operating connections for the signal members,

Fig. 4 is a perspective view of one of the 50 signal members detached, the connecting member for the signal members being broken away,

Fig. 5 is a view in perspective of the other signal member with a portion of the 55 connecting member,

Fig. 6 is a vertical sectional view of the device shown in Fig. 2,

Fig. 7 is a horizontal sectional view taken substantially upon line VII—VII of Fig. 6, 60

Fig. 8 is a sectional view illustrating somewhat diagrammatically a modification of the invention.

My invention broadly consists in a tower 10, of any suitable form in horizontal cross 65 section, mounted upon the top of a tubular column or post 11 which is vertically positioned at a street crossing provided, as herein illustrated, with separate street car lines 12 and 13.

The tower 10, when the device is constructed for receiving an occupant, has a floor 14 positioned above and spaced from the bottom 15 of the tower, providing a chamber 16 between said floor and bottom. 70 The inclosed portion 17 of the tower is connected to the roof or dome 18 by four posts 19 providing window openings 20 between the posts.

An annular connecting member or ring 21 80 is rotatably mounted in the bead 22 provided in the lower portion of the tower 10, and this ring connects a pair of oppositely disposed arcuate signal plates 23 which conform in contour to that of the tower 10 and 85 have the word "Cross" or other equivalent order painted or otherwise placed thereon. The signal plates 23 are vertically slotted as at 24 intermediate their ends and are provided with lugs 25 to which are pivoted the 90 signal arms 26 which have their inner ends disposed within the slots 24 and are prevented from swinging downwardly below a horizontal position by means of the stop lugs 27 provided on said signal plates 23. The 95 arms 26 have the word "Stop" suitably placed thereon and may be swung upwardly to an inoperative position as shown in Fig. 2 wherein they are suitably retained by such means as the latches 28.

A shaft 29 is journaled upright through the column 11 and floor 14, being provided with an operating handle 30 within the tower 10 for turning the shaft or being connected with a suitable operating means arranged within the sidewalk operating station 31 when the tower is constructed as in Fig. 1 unintended for the accommodation of an occupant therein. The tower 10 is provided with four equally spaced radially ar- 100 105 110

ranged reflectors 32 having lamps 33 positioned therein so as to illuminate the signals at night. Secured upon the shaft 29 within the chamber 16 is a pulley 34 having a 5 flexible member 35 passed therearound, one portion of said cable being directed downwardly through the slot 36 of the tower 10 and around the pulley 37, the same having its free end attached as at 38 to one of the 10 signal plates 23 as shown in Fig. 7. The other portion of the flexible member is similarly directed through the slot 36 and then passed partially around the tower 10 in an opposite direction, the same being attached 15 as at 39 to the other signal plate 23. If desired, the flexible member 35 may also extend between the points of connection 38 and 39 as at 35' in Fig. 7 to insure simultaneous movement of the signal plates 23 about the 20 tower 10, in which case the member 21 may be formed in two arcuate pieces equal in length to the signal plate 23 to which the same is attached. By reason of the above construction, it will be seen that when the 25 shaft 29 is rotated in one direction, the flexible member 35 will move as indicated by the arrows —a— in Fig. 7 so as to cause the arms 26 and plates 23 to rotate in the direction of the arrows —b— and thereby assume the position shown by dotted lines in 30 said Fig. 7. When this is done, the street which was previously closed to traffic by having the "stop" signals 26 presented to view, is now open to traffic by having the 35 "cross" signal plates 23 presented to view. Obviously, a reverse rotation of the shaft 29 will cause the signal to again assume its full line position as shown in Fig. 7.

For ventilation and other purposes, the 40 tower 10 has an open top 39 which is substantially closed by a plate 40 disposed thereabove and fastened to the arch member 41 suitably mounted within the upper chamber 42 of the tower 10. A mechanism 45 43 not forming part of the present invention but specifically defined in my application filed on even date herewith is operatively connected with the shaft 29 so as to operate a whistle or other audible alarm 44 50 whereby two impulses are given when the signal is set in one position and one is given when the signal is set in its other position.

Access may be had to the interior of the tower 10 through the door closed openings 55 45 provided in the floor 14 and bottom 15, it being noted that the traffic officer or operator may mount the ladder 46 so as to gain this position from the ground.

In Fig. 8, a modified form of operating 60 means for the signal plates 23 and arms 26 is shown which consists in fastening a large spur gear 47 upon the shaft 29, said gear 47 meshing with a pinion 48 suitably journaled in the chamber 16 and in turn meshing with 65 a surrounding internal gear ring 49 rigidly

fastened to the signal plates 23. By operating the wheel 50, it will be readily seen that the signal arms and plates may be rotated in one direction entirely instead of oscillated as is the case with the form of the invention 70 shown in Figs. 2 to 7 inclusive.

It is believed that the construction and operation of the present invention will be readily understood by those skilled in the art from the foregoing description and while 75 the forms of the invention herein shown and described are what are believed to be the preferable embodiments thereof, it is nevertheless to be understood that minor changes may be made therein without departing from 80 the spirit and scope of the invention as claimed.

What I claim as new is:—

1. A traffic signal tower adapted to be mounted at the intersection of streets and 85 comprising a tower having curved cross signals arranged at opposite sides thereof and suitably mounted for movement thereabout, outwardly extending stop signals carried by said cross signals so as to move therewith, 90 and means to simultaneously move said signals about said tower.

2. A traffic signal tower adapted to be mounted at the intersection of streets and comprising a cylindrical tower having curved 95 cross signals arranged at opposite sides thereof and suitably mounted for movement thereabout, outwardly extending stop signals carried by said cross signals so as to move therewith, means to simultaneously move said 100 signals about said tower, said stop signals being pivoted to said cross signals to swing upwardly to an inoperative position adjacent the tower, means to limit the outward and downward movement of said stop signals, 105 and means to retain said stop signals in their upward inoperative position.

3. A traffic signal tower including a tower adapted to be mounted at the intersections of streets, a shaft journaled upright in said 110 tower, means to rotate said shaft, arcuate signal plates mounted to move about said tower, outwardly extending signal plates carried by said arcuate signal plates, and operative connections within said tower between said shaft and the arcuate signal plates.

4. A traffic signal tower including a tower having a pair of oppositely disposed signal plates mounted to move thereabout, outwardly extending radial signal plates carried by said first named signal plates, a shaft journaled upright within said tower, a pulley mounted on said shaft, and a flexible member passed about said pulley and operatively connected to said signal plates whereby rotation of said shaft will cause movement of the signal plates about said tower.

5. A traffic signal including a tower hav- 130

ing a pair of oppositely disposed signal plates mounted to move thereabout, outwardly extending radial signal plates carried by said first named signal plates, and means 5 to simultaneously move said signal plates about the tower, whereby the sides of the second named signal plates will be seen by a

driver traveling in either direction upon one of a pair of intersecting streets while the first named signal plates will be seen by a 10 driver on the other of said intersecting streets.

In testimony whereof I affix my signature.
SOREN CHRISTIAN REPSHOLDT.
